UNITED STATES PATENT OFFICE.

JAMES G. DICKSON, OF CHICAGO, ILLINOIS.

CHECK-BOOK HOLDER.

SPECIFICATION forming part of Letters Patent No. 762,393, dated June 14, 1904.

Application filed November 21, 1903. Serial No. 182,076. (No model.)

To all whom it may concern:

Be it known that I, JAMES G. DICKSON, a citizen of the United States of America, and a resident of Chicago, in the county of Cook and State of Illinois, have invented certain new and useful Improvements in Check-Book Holders, of which the following is a specification.

The present invention relates to check-book holders for the use of bank depositors, and has for its object to provide a simple and convenient holder for a number of checks and in which means is afforded for keeping an accurate and convenient account of the money checked out by the depositor, all as will hereinafter more fully appear and be more particularly pointed out in the claim. I attain such object by the construction and arrangement of parts illustrated in the accompanying drawings, in which—

Figure 1 is a plan view of a holder in an open condition. Fig. 2 is an enlarged section at line *x x*, Fig. 1.

Similar numerals of reference indicate like parts in both views.

Referring to the drawings, 1 represents the back portion or member of the present check-book holder, provided at one end with an open-ended holding-pocket 2, of a substantially rectangular form and which is adapted to elastically grip and hold one end of a block 3 of bank-checks. In the present improvement such resilient pocket is formed by an angular flange or bend 1' of the back member 1, an overhanging lap or bend 1" at the upper end 35 of the flange 1' aforesaid, and a longitudinally-extending fold or rib 1''' at the free end of the lap or bend 1" aforesaid. With such construction the overhanging resilient lap or bend 1" bears, by means of its rib 1''', upon the stub 40 end of the block 3 of checks to securely clamp the same in place upon the back member 1 of

the holder by the resiliency of the material comprising the bands 1' and 1" aforesaid.

4 is a cover portion for the holder, hinged in any usual manner to the end of the top lap 45 of the pocket 2. Such cover portion is in the present improvement provided with marginal flanges 5, which form on the under side of said cover portion a holding-pocket for a series of loose sheets 6, which are properly ruled 50 for keeping in a convenient manner a record of the date, amount, and to whom the checks were issued.

With the present improvement as a block 55 of checks 3 are used up the same can be readily replaced by a fresh supply, and in like manner when the loose record-sheets are fully entered with the nature of the checks drawn they can be filed away and fresh sheets substituted in their place.

Having thus fully described my said invention, what I claim as new, and desire to secure by Letters Patent, is—

A check-book holder, comprising a back member provided with an open-ended pocket 65 of resilient material, such pocket consisting of an angularly-arranged flange on the back member, an overhanging lap on said flange, and a longitudinal rib on the inner face and free end of said lap, the said flange, lap and 70 rib having an integral formation and the lap and flange affording elasticity to the pocket, and a cover member connected to the free end of the lap aforesaid and adapted to carry a series of record-sheets, as and for the purpose 75 set forth.

Signed at Chicago, Illinois, this 19th day of November, 1903.

JAMES G. DICKSON.
